UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

SPECIFICATION forming part of Letters Patent No. 794,935, dated July 18, 1905.

Application filed November 1, 1904. Serial No. 230,897.

To all whom it may concern:

Be it known that I, MONROE GUETT, a citizen of the United States of America, residing at Hartford, in the county of Hartford and State of Connecticut, have invented certain new and useful Improvements in Electric Switches, of which the following is a specification.

The invention relates to electric switches in general, and is particularly adaptable to what is known as a "push-button" switch.

The object of the invention is to provide an article of the class specified having features of novelty and advantage, an especial feature of novelty and advantage in my present switch being that by a single push-button the moving member of the switch is rotated in successive steps in one direction.

An embodiment of my invention is illustrated in the drawings, in which—

Figure 1 is a plan view of the base-plate. Fig. 2 is a detail view of the rack and pinion, showing the push-button in section. Fig. 2^a is a side elevation of the pinion, showing the spring-arm. Fig. 3 is a plan and side elevation of the spring-plate. Fig. 4 is a plan and side view of the spring detent-plate. Fig. 5 is a detail plan view showing the collocation of the locking-lever, the stop-lever, the spring-plate, and the stop-plate. Fig. 6 is a plan view of the poles. Fig. 7 is a general plan view of the assembled switch. Fig. 8 is an edge view looking from the bottom of Fig. 7.

Referring to the drawings, *a* denotes the base, which supports the switch mechanism and which may be suitably mounted, as on a block of insulating material *a'*. This base supports a spindle *b*, mounted so that it is free to oscillate or turn forward and backward in said base. Fixedly mounted on the spindle *b* is the segmental pinion *c*, having the downwardly-projecting spring-arm *c'*. The pinion meshes with a rack *d*, which is connected with and moved by the push-button *d'* and has a slot *d''*, which terminates in a cam-opening *d'''*.

Loosely mounted on the spindle immediately above the pinion is the spring-plate *e*,

having the downwardly-projecting spring-arm *e'*, which normally overlies the spring-arm *c'* on the pinion *c*. This spring-plate has a tripping projection *e''*, the purpose of which will be more fully described hereinafter. The spring-plate has also the peripheral notches *e'''* to receive the downturned fingers *f'* on the detent-plate *f*, thus securing said detent-plate to said spring-plate. This detent-plate has the spring-detents *f''*, adapted to engage teeth on the stop-plate *g*.

The stop-plate *g* carries the poles *i* and is loosely mounted on the spindle above the spring detent-plate. It has peripheral notches formed, as shown, by the teeth *g'* *g''*, the teeth *g'* being the ones which are engaged by the spring-detents *f''* to form a driving connection between the spring-plate *e* and the poles *g*. Pivoted on the base is the lever *l*, having a pin *l'* projecting from its under side into the slot *d''* in the rack *d* and having an arm carrying a tooth *l''*, which engages with the notches in the periphery of the stop-plate. The stop-lever *r* is also mounted on the base and has a stop projection *r'*, which is thrown into the path of movement of the tooth *g'* by the tripping projection *e''* on the spring-plate *e* to determine the amount of movement of the stop-plate and poles at each throw of the switch. A pin *a'* on the base *a* projects into the slot *d''* in the rack *d* to guide its movement.

A spring *s* is coiled about the spindle *b*, with its ends lying on each side of the spring-arms *c' e'*. A second coil-spring *s'* has one end in engagement with the spring-arm *c'* on the pinion and its other end engaging a stationary part.

The operation of the device is as follows, the parts being shown in their normal positions in Fig. 7, where it will be seen that the tooth *l''* on the arm of the lever *l* is in engagement with one of the notches in the stop-plate, and consequently that the spring-plate *e* is held against movement because of its connection with the stop-plate through the detent-plate *f*. It will also be seen that the pin

¹ on the lever ^l rides in the straight part of the slot ^{d²} in the rack ^d. Pressure on the push-button moves the rack down and turns the pinion, the spring-arm ^c carrying one ⁵ end of the spring ^s around, winding it up on the spindle. When the pin ^l rides in the cam-slot ^{d³}, it throws the lever ^l to the left and disengages the tooth from the stop-plate, at which time, the spring ^s having been sufficiently compressed, the poles and stop-plate, the detent-plate, and the spring-plate are thrown by said spring. As the spring-plate moves around its tripping projection ^{e²} strikes the upper arm ^{r²} of the stop-lever ^r, moving ¹⁵ the stop projection ^{r'} into the path of movement of a tooth ^{g'}. As the parts snap forward, carrying the poles to a new position, the spring ^s is wound up on the spindle, and when the push-button is released this spring ²⁰ causes the pinion to move backward, moving the rack up, the cam ^{d³} by means of the pin ^l throwing the lever ^l to the right and bringing the tooth ^{r'} into engagement with a notch in the stop-plate ^g, the trip projection ^{e²} on ²⁵ the spring-plate throwing the lower end of the stop-lever ^r out of the path of movement of the stop-plate, the parts returning to their normal positions (shown in Fig. 7) ready for operation again in the manner above described.

It will be noted that the only continuously-rotating parts of this mechanism are the poles and the stop-plate connected therewith, the detent-plate, spring-plate, pinion, and spindle having merely an oscillating movement, the rack and push-button having a reciprocating movement, and the levers ^l and ^r having a rocking movement.

I am aware that the structure as herein described may be modified and that the shapes or construction of some of the parts can be altered without departing from the spirit of my invention.

I claim as my invention—

⁴⁵ 1. In an electric switch the base, the oscillating spindle mounted therein, a rack having a push-button, a pinion secured to said spindle and meshing with said rack, poles, and driving connections between said pinion and said poles.

⁵⁰ 2. In an electric switch in combination the base, the oscillating spindle mounted therein, a pinion secured to the spindle, poles loosely mounted on the spindle, a rack meshing with said pinion, a push-button on said rack, means for holding the poles against movement during the initial movement of the rack and pinion, means for releasing the poles at a predetermined time, and a forward driving connection between the poles and the pinion, substantially as described.

⁵⁵ 3. In an electric switch in combination the base, an oscillating spindle mounted therein, a pinion secured to the spindle, poles loosely

mounted on the spindle, a rack meshing with ⁶⁵ the pinion, a push-button on the rack, means for holding said poles stationary during the initial movement of the rack and pinion, a spring having one end in engagement with the pinion whereby said spring is made tense during the initial movement of the rack and pinion, means for releasing the rack, and a second spring to return the parts to normal position. ⁷⁰

⁷⁵ 4. In an electric switch in combination the base, the oscillating spindle mounted therein, the pinion secured to the spindle, poles loosely mounted on the spindle, the rack meshing with the pinion, the push-button on the rack, stops secured to said poles, a pivotally-supported lever having an arm in engagement with said stops, forward driving connections between the pinion and the poles, a spring having one end in engagement with the pinion and the other end in engagement with the poles, means ⁸⁰ for disengaging said lever from the stops, and a spring to return the parts to normal position. ⁸⁵

⁹⁰ 5. In an electric switch the base, the oscillating spindle mounted therein, the pinion, secured to the spindle and having a spring-arm, a spring-plate loosely mounted on the spindle and having a spring-arm, a detent-plate secured to said spring-plate, a stop-plate loosely mounted on the spindle and adapted for engagement with said detent-plate, poles secured to said stop-plate, a rack in engagement with said pinion and having a cam-slot, a push-button on said rack, a pivotally-supported lever having one arm in engagement with the stops on the stop-plate, and a pin cooperating with ¹⁰⁰ said cam-slot, a spring having its ends lying on opposite sides of the spring-arms on the pinion and spring-plate, and a second spring to return the parts to normal position. ⁹⁵

¹⁰⁵ 6. In an electric switch the base, the oscillating spindle mounted therein, the pinion, secured to the spindle and having a spring-arm, a spring-plate loosely mounted on the spindle and having a spring-arm, a detent-plate secured to said spring-plate, a stop-plate loosely mounted on the spindle and adapted for engagement with said detent-plate, poles secured to said stop-plate, a rack in engagement with said pinion and having a cam-slot, a push-button on said rack, a pivotally-supported lever having one arm in engagement with the stops on the stop-plate, and a pin cooperating with ¹¹⁰ said cam-slot, a spring having its ends lying on opposite sides of the spring-arms on the pinion and spring-plate, and a second spring to return the parts to normal position, and a stop to determine the amount of movement of the poles at each turn. ¹¹⁵

¹²⁰ 7. In an electric switch in combination the base, the oscillating spindle mounted therein, a pinion secured to said spindle, poles loosely mounted on the spindle, a rack in engagement with the pinion, a push-button on the rack, a ¹²⁵

spring-plate loosely mounted on the spindle above the pinion, a stop-lever carrying a stop adapted to coöperate with said poles to limit the amount of movement at each throw, and 5 a trip projection on said spring-plate coöperating with said stop-lever, substantially as described and for the purposes set forth.

In testimony whereof I affix my signature in presence of two witnesses.

MONROE GUETT.
